UNITED STATES PATENT OFFICE

JORDAN D. STANTON, OF BERKELEY, CALIFORNIA, ASSIGNOR OF ONE-HALF TO I. G. KRIEGER, OF LODI, CALIFORNIA

COLLAPSIBLE COVER

Application filed March 26, 1927. Serial No. 178,635.

This invention relates to improvements in cover devices for typewriters and similar machines, my principal object being to provide a cover structure permanently mounted in connection with the machine, so arranged that such machine may be completely enclosed and protected with a single almost instantaneous performed movement, without having to shift the machine or having to adjust the cover to fit.

A further object is to provide a device of this character of such a nature that when it is thrown back to uncover the machine said cover will be then disposed so as not to interfere with the necessary manipulation of the operating parts of the machine, and will be automatically held against any movement in a covering direction.

A further object of the invention is to provide a cover which may be locked in its closed position if desired, so that the machine cannot be easily tampered with. The cover may also be readily mounted in connection with any standard typewriter and when in place either in its enveloping or uncovering positions will present a neat and attractive appearance.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a perspective elevation of my cover as detached from a machine and with its collapsible cover portion thrown back or collapsed.

Fig. 2 is a transverse section of the device as mounted in connection with a typewriter, the cover member being in its extended or covering position.

Fig. 3 is an enlarged fragmentary view showing a mounting means for the lower end of the collapsible cover and the front bow of the same.

Fig. 4 is an enlarged fragmentary sectional plan taken on the line 4-4 of Fig. 1.

Referring now more particularly to the characters of reference on the drawings, the numeral 1 denotes a base plate adapted to be disposed under a typewriter 2 between the front and rear feet 3 thereof and then extending beyond both sides of the typewriter a certain distance.

The plate 1 is adapted to be detachably but firmly mounted on the supporting element 4 which also supports the typewriter, by means of studs 5 arranged to be fixed in and project upwardly from said element through the plate 1 and to be engaged by finger nuts 6 above the plate. At its sides the plate 1 has upstanding flanges 7 which have longitudinal slots 8 therein.

Disposed rearwardly of the base plate and behind the typewriter is a cover supporting structure comprising a vertical back plate 9 of a height to extend above the top of the machine and of a width greater than that of said machine; said back plate having triangular side wings 10 sloping downwardly and forwardly therefrom to the base plate. Forwardly projecting extensions 11 are attached to the lower ends of the wings and are slidable between the flanges 7, said extensions having lateral pins 12 engaging the slots 8 in said flanges.

Projecting toward each other from the forward edges of the wings, and also downwardly from the top of the back plate, is a continuous flange 13, whose whole extent lies in the same angular plane as the forward edges of the wings. Secured to and projecting forwardly from the lower ends of the side flanges 13 are rods 14 or the like arranged to form enclosed eyes or loops with said flanges. Engaging and turnably mounted on said eyes as an axis is a three sided rectangular frame 15, the exterior dimensions of which are the same as the corresponding dimensions of the back plate and wings. The frames 15 and the flange 13 form the front and back bows respectively of a collapsible cover structure 16, and said bows are of double construction so as to enable the opposite ends of said cover to be clamped between the two thick-

nesses of the bows. The cover structure 16 is of rectangular form, corresponding to the bows and is preferably of the well known bellows or accordion pleat construction. The 5 pleats or folds of the cover are orificed so that the upper portions of the rods 14 (which also engage the bow 15) pass freely therethrough. The interior size of the bow 15 and of course the cover also is such as to clear all parts of 10 the typewriter. The top bar of the bow 15 is provided with an outwardly projecting handle member 17.

In operation when not in use the front bow is raised and swung upwardly and rearwardly, a movement which causes the pleats 15 of the cover to fold. When the bow has moved in this direction until the cover is snugly folded (at which time the bow 15 will be substantially parallel to the bow 13) said bow 15 on its inside and at the corners is engaged by spring catches 18 which are secured to the back plate 9 and project forwardly the necessary distance. This leaves the typewriter exposed, enabling the same 20 to be manipulated as may be necessary and preventing the cover from possibly opening out of itself.

When it is desired to cover the machine the catches 18 are released and the handle 17 30 is drawn downwardly and forwardly until the bow 15 rests on the supporting surface 4 in front of the typewriter. With this movement the cover 16 will be unfolded and will move through a substantially circular 35 arc, owing to the substantially axial connection of the bow and cover with the members 14. To then enable the cover to be locked in its enveloping position if desired, I provide a bar 19 slidably mounted on the 40 base plate 1 and projecting forwardly therefrom. This bar has an upwardly projecting orificed tongue 20 at its outer forward end, adapted to pass through a slot 21 provided in the handle member 17. If after the tongue 45 is thus engaged the shank of a padlock is placed through the tongue orifice the cover can not be raised, as will be evident. By reason of the sliding mounting of the lock bar 19 the latter may be retracted sufficiently 50 when not in use so as not to be in the way of the operator manipulating the typewriter. By reason of the sliding mounting of the cover supporting structure on the fixed base the said structure may be moved rearwardly 55 of the typewriter somewhat when the cover is raised so as to give more room for the operation of the machine if desired, and also enabling the same size cover structure to be applied to typewriters differing somewhat in 60 depth.

Said cover supporting structure may also be used to support a copy holding device, such as a pair of vertical rods 22 connected by an integral top cross bar 22^a. The rods 65 are slidably mounted for vertical movement

in connection with the back plate 9 just in front of the same, and project through the metal between the plate and the adjacent flange 13. The rods tend to spring apart and are notched at intervals on their opposite sides as at 23 so as to engage the metal through which the rods pass and thus enable the holder to be set and maintained at different heights.

From the foregoing description it will be 75 readily seen that I have produced such a device as substantially fulfills the objects of the invention, as set forth herein.

While this specification sets forth in detail the present and preferred construction 80 of the device, still in practice such deviations from such detail may be resorted to as do not form a departure from the spirit of the invention, as defined by the appended claims.

Having thus described my invention what 85 I claim as new and useful and desire to secure by Letters Patent is:

1. In a collapsible cover structure, a base plate, a cover structure mounted on the plate for horizontal movement to and from the front of the plate, said structure including a front bow arranged to be lowered to or raised from the plate, a slotted element projecting outwardly from the bow, a bar on the plate, a tongue on the outer end of the bar to engage the slotted element when the front bow is lowered, and means connecting the bar to the plate in a manner to permit of adjustment of the bar on the plate to the same extent and in the same direction as the 95 movement of the cover structure relative to the plate.

2. In a collapsible cover structure, a substantially vertical back bow, rigid eye members whose upper portions are substantially 105 straight and horizontal projecting forwardly from the back bow adjacent the base thereof, a front bow swivelly mounted on said eyes, and a flexible collapsible cover connected to and extending between the bows. 110

3. In connection with a collapsible cover structure, a rigid vertical back plate, forwardly projecting side wings formed therewith at the ends thereof, and flanges turned inwardly along the top of the plate and the 115 forward edges of the wings to form the back bow for the cover structure.

In testimony whereof I affix my signature.
JORDAN D. STANTON.
